Golde & Schlesky
ATTORNEY

UNITED STATES PATENT OFFICE

SAM KRANZ, OF NEW YORK, N. Y.

ROLL SCREEN FASTENER

Application filed October 21, 1930. Serial No. 490,162.

This invention relates to new and useful improvements in a screen.

The general public prefers the rolled type of screen over the flat type in that when so designed it can take up a very much smaller compass. Further, the rolled type is adapted to various conditions not possible by the flat type, particularly in that it may cover the opening of a window which is opened to any desirable amount, very efficiently.

It is an object of this invention to provide a screen of the class mentioned which is of simple durable construction, dependable in use and efficient in action, and which can be manufactured and sold at a reasonable cost.

It is a further object of this invention to provide a screen of the class mentioned which includes a casing to house a spring roll holding screen material, and attachable upon a window frame or window sash, and provided with a coacting cover connected with the screen material and attachable either on the window frame or window sash so that the screen may cover any amount of window opening or may assume a position in which the window opening is unrestricted.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is an elevational view of a window seen from the outside and provided with screens constructed according to this invention.

Fig. 2 is a fragmentary enlarged sectional view taken on the line 2—2 of Fig. 1.

Fig. 3 is a fragmentary enlarged sectional view taken on the line 3—3 of Fig. 1.

Fig. 4 is a fragmentary enlarged sectional view as though taken on the line 4—4 of Fig. 1, but showing the screen retracted.

Fig. 5 is a fragmentary sectional view taken on the line 5—5 of Fig. 4.

Fig. 6 is a fragmentary enlarged sectional view taken on the line 6—6 of Fig. 1.

The screen according to this invention comprises a casing 10 having an opened side 11, means for attaching said casing upon a member, a spring wound roll of screen 12 within said casing, a cover 13 for closing the open side of the casing, and means for attaching said cover upon a member.

The casing 10 is of box shape and is of a length equal to the width of a window, for which it is intended, and of a width equal to the thickness of the particular window sash. The sides and the ends are of thin material, except the side 14 directly opposite the opening 11. This thick side is arranged as hereinafter further described so as to be provided with the means for accomplishing the attachment of the casing upon a member.

The means for accomplishing the attachment just mentioned in the latter part of the previous paragraph comprises catch strips 15 swivelled upon the thick side 14 and directly over cavities 16 in the thick side. The portions of the strips 15 beneath the cavities 16 are formed with elongated openings 17. The swivelling of the strips 15 is accomplished by leaf sections 18 attached upon the strips and extending into grooves formed in the thick side 14. It is necessary that a screw, such as 19, be attached upon the member to which the casing 10 is to be attached and that this screw have a head formed with a reduced portion 20 for receiving the elongated opening 17. In one position of the catch strips 15, the grooves 17 are in position so that the head 19 of the screw which is also elongated may pass through, but in an inclined position as shown in Fig. 5 the slot 17 is off line and serves to hold the parts together.

The screen roll comprises a conventional spring operated roll supporting screen material 22.

The cover 13 for the casing 10 is merely a flat member to which a guide bar 29 is attached, and serves to clamp one edge of the screen material 22. In the casing 10 there is a guide rod 30 which extends completely

from one end to the other end and serves to hold the web of the screen material 22 directly below the guide bar 29.

The means on the cover 13 for attaching it upon a member comprises screws 31 having heads of oblong shape which are reduced as at 32 to engage the strips 33 from catches attached upon said member. These catches comprise strips 33 which are swivelly mounted over cavities 34 into which the heads may extend. The strips 33 are formed with elongated openings 17 for the passage of the heads 31. The strips are also provided with leaf portions 18 to allow their swivelling as before recited relative to the catches which connect the casing 10 with the member.

In Fig. 1 the outside of a house has been shown, and particularly two windows. Both the windows are mounted in a common frame 35 and each comprises an inner sash 36 and an outer sash 37. These sashes are provided with window panes 38. Guide strips 39 are between the inner and outer sashes so as to keep them properly spaced, as is conventional construction. Other guide strips 40 are arranged to the front and to the rear of the guide strips 39 so as to form grooves in which the window sashes move.

In Fig. 1 the right hand window is shown with the outer sash partially down and with the screen material 22 extended across the opening, while the inner sash is shown in its completely lowered position. The left hand window is shown with its outer sash partially down, but with the cover 13 disconnected from the window frame so that the screen material does not extend across the opening. In the left hand window, the inner sash is shown partially raised with the cover 13 from the screen attached upon the lower edge of the sash so that the screen material covers the opening.

A detail of the outer sash construction is shown in Fig. 2. It should be recognized that the casing 10 is attached upon the top edge of the outer window sash by means of the catches which include the strips 15, while the cover 13 is attached upon the frame 35 by the catches which include the strips 33. As shown in Fig. 2, when the outer sash is lowered, the screen 22 will be drawn along to cover the opening. In the event that it is required to have the opening unrestricted, the strips 33 may be moved so that the screw heads 31 may pass through the slots in the strips and then we have the case as shown in the left hand window in Fig. 1, that is, with the cover 13 moving along with the casing 10 so that the screen is not extended.

The construction of the inner sash is clearly shown in Fig. 4, in which the lower edge of the sash is provided with the screws 19 and in which the casing 10 is upside down so that the strips 15 of the catches may engage these screws. In Fig. 4 the inner window sash is

shown disconnected from the casing 10 so that when the window is opened the screen will not follow. In the event that we do wish the screen to follow, as shown in the left hand window in Fig. 1, it is merely necessary to close the window sash and manipulate the catch strips 15 so that these parts interengage. Then when the window is raised, the casing 10 will be lifted along with the window sash and the screen extended.

If desired, the screen may be completely disconnected from the windows and stored away. For example, examining Fig. 4, if the strips 33 be moved so that the catches disengaged, then the casing 10 together with the cover 13 may be removed. Examining Fig. 2, the catch strips 33 may be moved so that the cover 13 is free and the catch strips 15 moved so that the casing 10 may be lifted from the window sash.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a screen, a casing for supporting a spring wound roll of screen and having an opened side, means for attaching said casing upon a member, said casing being of substantially box shape and having thin sides except the side opposite said opening which is very thick and formed with recessed portions to accommodate screw heads substantially as described.

2. In a screen, a casing for supporting a spring wound roll of screen and having an opened side, means for attaching said casing upon a member, said casing being of substantially box shape and having thin sides except the side opposite said opening which is very thick and formed with recessed portions to accommodate screw heads substantially as described, said means for attaching said casing upon a member comprising pivoted strips each formed with an opening for receiving the head of a screw in said member.

3. Means for attaching a screen casing upon the bottom edge of an inner window sash, said means including pivoted strips on the said casing formed with rectangular apertures engageable with rectangular shaped heads on screws attached upon the bottom of the window sash.

4. In a screen, a casing for supporting a spring wound roll of screen and having an opened side, means for attaching said casing upon a member, said casing being of substantially box shape and having thin sides except the side opposite said opening which is very thick and formed with recessed portions

- to accommodate screw heads substantially as described, said means for attaching said casing upon a member comprising catch strips having elongated openings swivelly attaching said strips to the thick side of the casing so that the elongated openings are over said recessed portion, and screws fixed in the said members and having elongated heads engageable in the elongated openings of the strips.
- 5 5. In a screen, a casing for supporting a spring wound roll of screen and having an opened side, means for attaching said casing upon a member, said casing being of substantially box shape and having thin sides except the side opposite said opening which is very thick and formed with recessed portions to accommodate screw heads substantially as described, said means for attaching 15 said casing upon a member comprising catch strips having elongated openings swivelly attaching said strips to the thick side of the casing so that the elongated openings are over said recessed portion, and screws fixed 20 in the said members and having elongated heads engageable in the elongated openings of the strips, said means for swivelling strips comprising leaf sections attached upon the strips and engageable in grooves formed in 25 the thick side of the casing.
- 30

In testimony whereof I have affixed my signature.

SAM KRANZ.
